[57] CLAIM

The ornamental design for a crib footboard, as shown and described.

DESCRIPTION

FIG. 1 is a front elevational view of a crib footboard, showing my new design;

FIG. 2 is a side elevational view, the opposite side being identical thereto;

FIG. 3 is a top plan view thereof;

FIG. 4 is a bottom plan view thereof;

FIG. 5 is a sectional view taken along line 5—5 in FIG. 1;

FIG. 6 is a sectional view taken along line 6—6 in FIG. 1;

FIG. 7 is a sectional view taken along line 7—7 in FIG. 1;

FIG. 8 is a sectional view taken along line 8—8 in FIG. 1;

FIG. 9 is a sectional view taken along line 9—9 in FIG. 1.

The sectional views shown in FIGS. 5-9 have been drawn to an enlarged scale with respect to FIG. 1.
